UNITED STATES PATENT OFFICE.

VICTOR R. WILLOUGHBY, OF RIDGEWOOD, NEW JERSEY, ASSIGNOR TO AMERICAN CAR AND FOUNDRY COMPANY, OF ST. LOUIS, MISSOURI, A CORPORATION OF NEW JERSEY.

TANK-DISCHARGE-VALVE MECHANISM.

Application filed January 26, 1921. Serial No. 439,917.

To all whom it may concern:

Be it known that I, VICTOR R. WILLOUGHBY, residing at Ridgewood, Bergen County, New Jersey, and being a citizen of the 5 United States, have invented certain new and useful Improvements in a Tank-Discharge-Valve Mechanism, of which the following is a full, clear, and exact description, such as will enable others skilled in 10 the art to which it appertains to make and to use the same, reference being had to the accompanying drawings, which illustrate the preferred form of the invention, though it is to be understood that the invention is 15 not limited to the exact details of construction shown and described, as it is obvious that various modifications thereof within the scope of the claims will occur to persons skilled in the art.

20 In said drawings:

Figure 1 is a vertical longitudinal section taken on line 1—1 of Fig. 2 looking in the direction indicated by the arrow, and showing a preferred embodiment of my invention 25 with the valve in locked closed position;

Figure 2 is a plan view of the same;

Figure 3 is a horizontal section taken on line 3—3 of Fig. 1 looking in the direction 30 indicated by the arrow;

Figure 4 is an elevational view of the invention showing the application thereof to the bottom of a tank;

Figure 5 is a view similar to Fig. 1 showing 35 the valve in closed position but unlocked; and

Figure 6 is a view similar to Fig. 1 showing the valve in full opened position.

My invention relates to the class of outlet 40 valves employed in tanks used for the transportation of oil, asphalt and like commodities, and is of the type adapted to prevent extraction of tank contents except upon manipulation of certain valve controlling 45 mechanism within the tank.

One object of my invention is to provide means for effecting the positive locking of the valve upon its seat through the medium of a reciprocating valve supporting mem-

ber having telescopic engagement with said 50 valve.

Another object is to provide means for permitting the valve to grind upon its seat prior to the locking thereof.

A further object is to protect the valve 55 member of the device by so arranging the part associated with the valve member as to prevent the ingress of matter tending to congeal in the space between said parts and to shield the interengaging threaded portions thereof from the bad effects of the tank 60 contents.

In said drawings, 10 represents a tank at the bottom of which is arranged the usual discharge outlet 11 with which is associated 65 a housing 12 threaded into the outlet as shown at 13. Housing 12 is provided with a number of openings 14 for the egress of the tank contents and supports within its confines a reciprocatory valve supporting 70 and locking member 15.

The valve supporting and locking member 15, while permitted to reciprocate within the housing 12, is held from rotation therein by means of the stud bolts 16 tapped 75 into the housing 12. The stud bolts 16 are each provided with protruding fingers 17 adapted to provide a loose or pin and slot connection between the housing 12 and valve locking member 15 through the medium of 80 slots 18 in the valve locking member into which slots said fingers 17 project.

Within the valve locking member 15 is threaded a reciprocatory and rotatory valve member 19 having a disc portion 20 to fit 85 upon valve-seat 21 and close discharge opening 22. The valve member 19 is shown with its disc portion 20 integral therewith but may, for greater convenience in manufacturing or assembling, be formed in separate 90 parts and suitably fitted together.

It will be noted that the valve locking member 15 is chambered as shown at 23 and 24 and provided with contracted portion 25 screw-tapped to receive threaded portion 26 95 of the valve member 19 and a contracted throat portion 27 adapted to engage valve member 19 with a neat fit.

Resting upon valve member 19 and operatively associated therewith is a shaft 28 extending upwardly through an opening 29 in the valve locking member with which it 5 engages at this point also with a neat fit. Shaft 28 is provided with a polygonal stud portion 30 entering the socket 31 of the valve member 19 for controlling the valve mechanism.

10 Assuming the valve to be in the locked closed position shown in Fig. 1, the shaft 28 is rotated to open the valve. During the initial period of rotation of said shaft, valve locking member 15, by virtue of its 15 threaded engagement with valve member 19 driven by said shaft, will fall until the upper ends of slots 18 contact with engaging fingers 17 of the stud bolts 16 when its further descent will be checked, said stage 20 of operation being shown in Fig. 5 of the drawings. During this period and range of movement of the valve locking member 15 the reciprocatory valve member 19, though 25 rotating with shaft 28, has not left the valve seat 21 but has been allowed to remain with its disc portion 20 grinding therein.

Continued rotation of shaft 28, with further downward movement of valve locking member 15 arrested, will cause valve member 30 19 to rise, carrying with it disc portion 20 and shaft 28, and thread its way upwardly into chamber 23 of the valve locking member 15 to the full open position shown in Fig. 6.

35 Upon reverse rotation of operating shaft 28, the valve member 19 will first move downwardly, threading its way in the relatively fixed locking member 15 until the disc portion 20 of the valve member rests in 40 valve seat 21, at which time the relative positions of the parts at this stage of movement is as shown in Fig. 5. Continued rotation of the shaft and valve member 19 will cause valve disc 20 to grind in valve seat 45 21, and the valve locking member 15, by virtue of its threaded engagement with valve member 19, to rise under the influence of the rotating valve member 19 until the bottom ends of slots 18 engage the undersides of fingers 17 of stud bolts 16, at 50 which time the downward pressure of the valve member 19 upon the valve seat 21 will have been translated into a pressure upwardly against the underside of fingers 55 17 through the medium of the inter-engaging threaded portions of the parts and the valve locked in the closed position shown in Fig. 1.

From the operation of the mechanism as 60 above outlined, it will be evident that at no time during the period of movement of valve member 19 and locking member 15 do said members have simultaneously reciprocal movements, but said parts will move 65 successively.

What I claim is:

1. In combination, a discharge outlet, a tubular valve housing having a valve seat mounted in said outlet, a valve adapted to engage said seat and a tubular valve locking member mounted in said housing and having threaded engagement with said valve and a portion adapted to guide said valve, said locking member being shifted longitudinally in said housing upon the 70 operation of said valve.

2. In combination, a discharge outlet, a tubular valve housing having a valve seat mounted in said outlet, a valve having a tubular stem adapted to engage said seat 80 and tubular valve locking member engaging said housing and valve and projecting from said housing and valve operating means projecting through said locking member to engage said valve.

3. In combination, a discharge outlet, a tubular valve housing having a valve seat mounted in said outlet, a valve having a tubular stem adapted to engage said seat, valve operating means adapted to engage 90 in said stem and tubular valve locking means engaging said housing and valve, said valve locking means being adapted to guide said valve and said operating means.

4. In combination, a discharge outlet, a 95 tubular valve housing having a valve seat mounted in said outlet, a valve having a tubular stem adapted to engage said seat, valve operating means adapted to engage said stem and tubular valve locking means 100 engaging said housing and valve and projecting from said housing to serve as a guide for said valve operating means.

5. In combination, a discharge outlet, a tubular valve housing mounted in said outlet, a valve having a tubular stem adapted 105 to seat in said housing, a valve locking member and means engaging said locking member and housing limiting the reciprocatory movement of said member in said housing, 110 said valve locking means forming a guiding means for said valve stem.

6. In combination, a discharge outlet, a tubular valve housing mounted in said outlet, a valve having a tubular stem adapted 115 to seat in said housing, a valve locking member having a limited reciprocatory movement in said housing and a detachable operating means for said valve, said valve locking means having means adapted to 120 cause reciprocation of said valve upon rotation of said valve and separate guiding means for said valve stem and valve operating means.

7. In combination, a discharge outlet, a 125 tubular valve housing having a valve seat mounted in said outlet, a valve adapted to engage said seat, a tubular valve locking member between said valve and housing guiding said valve in said housing and 130

adapted to have a limited longitudinal movement with respect to said valve and housing upon the operation of said valve. 10

8. In combination, a discharge outlet, a tubular valve housing having a valve seat mounted in said outlet, a valve adapted to engage said seat and a tubular valve locking means having a connection with said hous-

ing permitting a predetermined rotation of said valve on said seat.

In witness whereof I have hereunto set my hand in the presence of two witnesses.

VICTOR R. WILLOUGHBY.
